UNITED STATES PATENT OFFICE.

BUDD BRONSON, OF LAKWOOD, OHIO, ASSIGNOR TO THE OHIO RUBBER COMPANY, OF CLEVELAND, OHIO, A CORPORATION OF OHIO.

RUNNING BOARD.

Application filed October 17, 1925. Serial No. 62,981.

This invention relates to running boards for automobiles, and has for one of its objects to reduce the number of parts and the number of operations in constructing, finishing and applying running boards to automobile chassis.

A further object is to provide a running board having a non-metallic covering which will not loosen or buckle, and which is in effect a part of the running board instead of being applied and fastened to it as ordinarily.

A still further object is to provide a running board having a rubber covering which in effect is formed integral with it, and which is tougher and has greater abrasive resistance than when the covering is cemented to the running board.

Still further the invention aims to do away with the necessity of the usual metal binding strip employed in connection with a non-metallic covering, and to eliminate the necessity for rivets, screws and the like ordinarily employed in applying the binding strip.

The invention may be briefly summarized as consisting in certain novel details of construction, and combinations and arrangements of parts which will be described in the specification and set forth in the appended claims.

In the accompanying sheet of drawings, Fig. 1 is a perspective view of a portion of an automobile provided with a running board embodying the invention; Fig. 2 is a top plan view of the running board with part of the rubber covering removed to show the metal base to which the covering is molded, vulcanized and interlocked; Fig. 3 is a transverse sectional view of the same on a slightly enlarged scale; Fig. 4 is a perspective view of a portion of the base of the running board with the rubber covering removed; Fig. 5 is a detail sectional view through the base, substantially along the line 5-5 of Fig. 2, showing one of the struck-up straps used in forming the interlock between the rubber and metal, the rubber covering being omitted; Fig. 6 is a similar detail sectional view through the rubber and metal parts of the running board, the section being taken between the interlocking straps; Fig. 7 is a similar view with the section taken

through one of the interlocking straps; and Figs. 8, 9 and 10 are detail sectional views on an enlarged scale, through the marginal portion of the base or metal portion of the running board, and illustrating different ways in which the margin may be formed or treated.

Referring now to the drawings, 10 represents my improved running board adapted to be applied to the motor vehicle, a portion of which is indicated at 11, and which includes front and rear fenders 11^a and 11^b which are attached to the ends of the running board 10. The running board may be supported from the chassis frame in any suitable manner, as by one or more arms or brackets projecting out from the chassis frame and secured in any of the usual ways to the lower side of the running board. As my invention does not involve the manner of attaching the running board to the chassis frame, a mode of attachment is not illustrated.

It is a feature of the present invention that the running board 10 is composed of a suitably shaped metal base or body 12 and a covering 13 of non-metallic material such as rubber which is molded and vulcanized to the base 12 so as to in effect form an integral part therewith.

The metal board or base 12 of the running board is preferably stamped from sheet metal of suitable gauge, and in the stamping or forming operation it is given the shape hereinafter described to accommodate the rubber covering, and is suitably deformed at intervals to cause the rubber and metal to be thoroughly interlocked together. The rubber covering 13, which is preferably ribbed, as shown, is molded directly onto the base 12, which acts as one part of the mold, and this is accomplished in a suitable hydraulic press, preferably a vulcanizing press, as it is desirable that the rubber be vulcanized under the pressure required to mold it to the proper shape on the base.

In stamping out the base or metal portion of the running board, it is preferably made in the form of a shallow receptacle or pan, as best indicated in Fig. 3, with at least four distinct objects in view, to-wit; to accommodate the rubber covering, to form finished edges at the margin of the top of the run-

ning board; to give increased strength over present methods of forming the metal; and to interlock the metal and rubber. In shaping the metal to accomplish these ends, the 5 metal is formed with a bottom 12^a, and on all four sides with a continuous upstanding marginal rim or flange 12^b, which in effect forms the sides of the shallow receptacle referred to. The bottom 12^a constituting 10 the base of the depression is generally flat notwithstanding the fact that it may be provided with grooves as later explained and the depression is of substantially uniform depth beneath the upper edge of the marginal rim or flange 12^b. The upstanding rim may be rounded as indicated in Fig. 3 and in Fig. 9; or it may be arranged square at the top, as indicated at 12^c in Fig. 8. The edge portions of the metal are preferably 15 turned down entirely around the running board, as indicated at 12^d, so as to give the requisite depth to the running board, and for strengthening purposes. The extreme edge portions may be turned inward, as indicated at 12^e in Fig. 9, or they may be folded up or turned back against the vertical marginal portions 12^d, as indicated at 12^f in Fig. 10. Furthermore, across the bottom 12^a I prefer to provide a series of longitudinal 20 and transversely extending intersecting grooves which may be rounded as indicated at 12^g in Figs. 3, 7 and 9, or may be made substantially square, as indicated at 12^h in Fig. 8. The principal function of these 25 grooves is to strengthen the running board, but as they are adapted to be filled with the rubber, they give more body to the rubber and assist materially in securing and holding the rubber and metal together.

30 Additionally in stamping or forming the metal part or base 12, the latter is given suitable deformations to form the interlock. In the preferred embodiment of the invention this is done by striking up what may be termed integral straps 12ⁱ, which bridge the longitudinal and transversely extending 35 grooves 12^g and are preferably elevated slightly above the bottom 12^a, as best indicated in Figs. 5 and 7. These struck up straps can be arranged as close together as is found desirable, and as indicated in Fig. 2 they are preferably arranged at regular or 40 substantially regular intervals, or uniformly over the base or body 12.

45 When the base 10 is placed in the press, and the rubber is molded onto it under very severe pressure, the rubber is squeezed and looped under all the straps 12ⁱ in the manner best indicated in Fig. 7, thus thoroughly 50 interlocking the metal and rubber. The interlocking may be formed in other ways as by punching suitable holes at intervals in the base or body 12, which holes can be made 55 regular or irregular as may be found desirable. However, I prefer to form the inter-

lock by striking up the straps 12ⁱ, which by bridging the grooves 12^g will be thoroughly embedded in the rubber without requiring that the rubber be made of unnecessary thickness.

As before stated, the rubber 13 is preferably ribbed, as illustrated, but it may be flat or any suitable design may be molded into the top of the rubber by the platen of the press, but the provision of ribs extending longitudinally of the running board is preferable. In molding the rubber to the metal part of the running board, the thickness of the rubber is preferably made substantially equal to the depth of the main depression of the running board,—that is to say, the top of the rubber is substantially flush with the upstanding marginal flanges or bead of the base or body 12, as best indicated in Fig. 3, but if desired, the top surface of the rubber may be slightly below or above the top of the marginal bead of the metal.

As running boards are ordinarily formed, a non-metallic covering of rubber or composition is cemented to the body of the running board, and a binding strip is utilized to hold the covering in place and to provide a trim or finish, the binding strip being usually held in place by screws, bolts or rivets.

In my improved construction it is obvious that no binding strip is required, as the finish is formed in the stamping and molding operation, leaving a metal bead all the way around the running board, the same being formed by the upstanding marginal rounded or otherwise shaped flange 12^b.

When the rubber is molded and vulcanized to the running board, no finishing operations are required in the way of painting or the like, as I propose to use steel treated to resist corrosion with a finish color such, for example, as silver-grey, satin-black, or any other color which may be desired for any particular automobile.

In applying a non-metallic covering to the running boards in use heretofore, great pains must be taken to reduce buckling, but in spite of the efforts made to prevent it, the coverings do loosen up, buckle or warp, but with my improved running board buckling or breaking loose is prevented in view of the fact that the rubber is molded into the shallow depression or pan-like metal body, vulcanized in place and thoroughly interlocked with the metal base practically uniformly over the entire surface thereof. Additionally the mode of applying the rubber makes it much tougher and increases the abrasive resistance with respect to a sheet of rubber applied in any other way, as by the methods heretofore used.

It will be noted that I have provided what might be termed a single unit steel and rubber running board completed in finished

form out of two substantially integral formed parts or elements, and adapted to be applied as a unit to the chassis of an automobile. In consequence, by my invention 5 not only the number of parts but the number of operations required in forming the running board are greatly reduced, thus enabling me not only to provide a very superior running board, but one which can be 10 produced inexpensively.

While I have shown the preferred construction, I do not desire to be confined to the precise details shown. For example, while the provision of grooves across the base 15 is preferable, in some instances they may be dispensed with, and while I prefer to provide the interlocking straps across the grooves, the straps may be formed independently of the grooves and may be distributed 20 over a base formed flat or with the grooves eliminated. While I have illustrated my invention applied to a running board for motor vehicles, I do not desire to limit my invention to the specific disclosure herein.

Having described my invention, I claim:

1. A composite product of the character described comprising a sheet metal body flanged at the margin and formed with a shallow depression having a generally flat 30 bottom surface of substantially uniform depth beneath the upper edge of said margin and a non-metallic sheet in contact with the body and substantially filling the said depression, said sheet in the molding operation 35 being interlocked with the body at spaced points along its margin and inside its margin so as to be held substantially uniformly

over its area against separation away from the base of the depression.

2. A composite steel and rubber running 40 board formed as a unit and comprising an elongated sheet metal body flanged and stiffened at its margin and formed with a shallow depression inside its margin, and a covering of rubber molded and vulcanized in 45 contact with the body and substantially filling said depression, the rubber having a thickened margin and in the molding operation being positively secured to the body at spaced points along the thickened margin 50 and at spaced points inside its margin by the rubber being extended beneath and interlocked with portions of the body, so as to be held substantially uniformly over its area against separation away from the base of the 55 depression.

3. A composite unitary running board comprising an elongated sheet metal body having a marginal wear resisting flange and a shallow, material-receiving depression having a generally flat bottom surface of substantially uniform depth beneath the upper edge of said margin, and a cover for said body molded in contact therewith and substantially filling said depression, said cover 60 being interlocked with said body at a plurality of points uniformly distributed over the surface of said depression, so as to prevent separation of the cover away from the base of the depression. 70

In testimony whereof, I hereunto affix my signature.

BUDD BRONSON.
